ATTORNEY

UNITED STATES PATENT OFFICE.

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA.

CONDENSER.

Application filed November 10, 1926. Serial No. 147,411.

This invention relates to steam condensers and more particularly to surface condensers in which the non-condensable fluids, such as air are separated from the condensable fluids and are cooled in an air cooling zone to as low a temperature and specific volume as possible prior to their delivery to the dry vacuum pump, which withdraws the air from the condenser.

10 An object of the present invention is to provide in a condenser as specified, means for preventing the flooding of the dry vacuum pump and securing the cooling and evacuation of the air in instances where the condensate rises to such level as to close the usual suction inlet to the air cooling zone of the condenser.

With these objects in view, the invention consists in various features of construction and combination of parts, which will be first described in connection with the accompanying drawings, showing a condenser of the preferred form embodying the invention, and the features forming the invention will 25 be specifically pointed out in the claims.

In the drawings—

Figure 1 is a side elevation partly in section of a condenser constructed in accordance with this invention.

20 Figure 2 is a cross section through a condenser constructed in accordance with this invention.

Figure 3 is an enlarged detail section through the condenser.

35 Figure 4 is a cross section through a modified form of the condenser.

Referring more particularly to the drawings, the improved type of surface condenser embodies a plurality of tubes 1 which extend longitudinally of the condenser shell 2 and through which cooling water is circulated.

40 In the form shown in Figures 1 to 3 of the drawings, baffle plates 3 and 4 are provided which diverge downwardly from the air suction pipe 5 and segregate a plurality of the tubes 1 to form the air cooling zone 6, at the lowermost portion of the condenser tubes so that the air passing over the tubes

in the air cooling zone 6 will be cooled to as low a temperature and specific volume as possible prior to its delivery through the suction 5 to the dry vacuum pump (not shown) which draws the air from the condenser.

45 The normal inlet of the air into the cooling zone 6 is across the bottom or lowermost edges of the baffles 3 and 4 as indicated by the arrows A in Figure 2 of the drawings. However, in instances where the condensate rises to such level as to close the usual suction inlets to the air cooling zone, the vacuum pump would be flooded and to prevent such flooding, a plurality of emergency inlets to the cooling zone 6 are provided.

50 In Figures 1 to 3 of the drawings the emergency entrances or inlets are formed by pipes 8 which are attached to and suitably supported by the baffles 3 and 4 above the lower edges of the baffles and between the normal air inlet to the air cooling zone 60 and the air suction or outlet 5. The pipes 8 extend from a point well within the tube nest or from among the tubes outside of the air cooling zone and these pipes may extend through the baffles, or to the baffles; in the 70 latter instances the baffles have suitable openings communicating with the pipes to permit the air to pass through the pipes into the cooling zone 6. To cause maximum cooling of the air entering the cooling zone 6 75 through the emergency inlets 8, the baffles 10 are provided which incline towards the normal air inlet and away from the air suction pipe 5 so as to cause the air to pass over as many tubes as possible during its passage 80 through the air cooling zone 6.

85 In Figure 4 of the drawings a modified form of the condenser is shown in which the air cooling zone 20 is positioned at one side of the condenser in lieu of the center of the 90 condenser as shown in Figures 1 to 3 inclusive. In the modified form of the invention where cooling zone 21 is confined by the baffle 22 which extends from the condenser shell 23 downwardly and inwardly 95 to approximately the vertical center of the

condenser, and entrance of air into the air cooling zone 21 is across or beneath the inner lower edge of the baffle 22 as indicated by the arrow B. The air suction 24 through which the air passes from the air cooling zone to the dry vacuum pump is directly beneath the uppermost portion of the baffle 22 and at the top of the air cooling zone 21. To permit passage of air from within the condenser into the cooling zone 21 when the condensate rises to such a level as to close the normal air inlet to the zone, (such condition being illustrated in the drawing) tubes or pipes 25 are provided which extend through the baffle 22 from within the tube nest outside of the air cooling zone to a mid-position within the air cooling zone. Baffles 26 are provided for directing the air which enters the cooling zone through the pipes or tubes 25, downwardly to cause it to pass over as large a number of tubes as possible prior to its passage through the air suction 24.

A drain 27 is shown for draining condensate from off the top of the baffle 22 to the hot well 28 of the condenser structure.

From the foregoing description taken in connection with the accompanying drawings, it will be apparent that a condenser structure has been provided which will prevent flooding of the dry vacuum pump in instances where the condensate rises to such level as to close the usual or normal inlet to the air cooling zone of the condenser and it will be understood that the invention is not to be limited to the specific construction or arrangement of parts shown but that these may be modified widely within the invention defined by the claims.

40. What is claimed is:

1. In a condenser, a plurality of cooling water receiving tubes, a baffle segregating certain of said tubes to form an air cooling zone, the normal inlet of air into said zone being across the lowermost edge of said baffle, said baffle having an emergency air inlet therein above its lowermost edge.

2. In a condenser, a plurality of cooling water receiving tubes, a baffle segregating certain of said tubes to form an air cooling zone, the normal inlet of air into said zone being across the lowermost edge of the baffle and a plurality of pipes extending from among the tubes outside of said zone and having communication with the zone through said baffle to provide emergency air inlets into the zone above the normal air inlet.

3. In a condenser, a plurality of cooling water receiving tubes, a baffle segregating certain of said tubes to form an air cooling zone, the normal inlet of air into said zone being at its lowermost portion, and outlet of air from said zone being at its uppermost portion, said baffle having a plurality of

emergency air inlet openings therein between the normal air inlet and the air outlet of said zone.

4. In a condenser, a plurality of cooling water receiving tubes, a baffle segregating certain of said tubes to form an air cooling zone, a plurality of pipes extending from among the tubes outside of said zone and having communication with the zone through said baffle to guide air into the air cooling zone, and baffle plates within the zone to direct air entering the zone through said pipes towards the normal air inlet to the zone.

5. In a condenser, a plurality of cooling water receiving tubes, a baffle segregating certain of said tubes to form an air cooling zone, a pipe having communication with the zone through said baffle to permit passage of air into said air cooling zone, and a baffle plate within the zone to direct air entering the zone through said pipe in a pre-determined direction in the zone.

6. A condenser including an air cooling zone having its normal air inlet at its lower portion and having an emergency air inlet spaced above the normal air inlet, and means within the zone for directing the passage of air from said emergency air inlet through said air cooling zone.

7. A condenser including an air cooling zone having normal air suction inlet at its lower portion and air outlet at its upper portion and having a plurality of emergency air inlets between the normal air inlet and air outlet, and means within the zone for directing air entering the zone through said emergency inlets away from the air outlet.

8. A condenser including an air cooling zone having normal air suction inlet at its lower portion and air outlet at its upper portion and having a plurality of emergency air inlets between the normal air inlet and air outlet, and a plurality of baffle plates within the zone for directing the passage of air entering the zone through said emergency inlets.

9. In a condenser, a plurality of water receiving tubes, a baffle segregating certain of said tubes to form an air cooling zone, a plurality of pipes extending from among the tubes outside of said zone and having communication with the zone through said baffle to form emergency air inlets into the cooling zone, and means within the cooling zone for directing the passage of air entering the zone through said emergency inlet pipes.

10. A condenser including an air cooling zone having normal air suction inlet and having an emergency air inlet spaced from the normal air inlet, and means within the zone for directing the passage of air from said emergency inlet through the air cooling zone.

11. A condenser including an air cooling

zone having normal air suction inlet and having an emergency air inlet spaced from the normal air inlet, and means within the zone for directing air entering the zone through the emergency inlet away from the air outlet of the zone.

12. A condenser including an air cooling zone having normal air suction inlet and

having an emergency air inlet spaced from the normal air inlet, and a baffle for directing air entering the zone through the emergency inlet away from the air outlet of the zone. ¹⁰

In testimony whereof I affix my signature.

JOHN F. GRACE.
